UNITED STATES PATENT OFFICE.

JESSE F. RELYEAE, OF BINGHAMTON, NEW YORK, ASSIGNOR, BY MESNE ASSIGNMENTS,
TO BONNIE BLAZE COMPANY, OF BINGHAMTON, NEW YORK.

DESIGN FOR A DECORATIVE FIREPLACE.

Application filed May 11, 1927. Serial No. 21,929. Term of patent 7 years.

To all whom it may concern:

Be it known that I, JESSE F. RELYEAE, a citizen of the United States, residing at Binghamton, county of Broome, State of New York, have invented a new, original, and ornamental Design for Decorative Fire-places, of which the following is a specification, reference being had to the accompanying drawing, forming a part thereof.

I claim:

The ornamental design for a decorative fireplace as shown.

JESSE F. RELYEAE.
